UNITED STATES PATENT OFFICE.

JAMES CLARENCE PATTERSON, OF EAST ORANGE, AND JAMES HENRY LYNCH, JR., OF JERSEY CITY, NEW JERSEY.

SWITCH-POINT PROTECTOR.

Application filed May 23, 1925. Serial No. 32,238.

Our invention relates to improvements in switch point protectors for railway switches or turnouts and consists in features of construction and arrangement designed to provide an improved device adapted to be efficient in eliminating or reducing wear and damage to switch points, to reduce derailments at switch points and the hazard and costs in connection therewith, to have adequate strength, to be economical of manufacture and to possess important advantages in operation over devices as heretofore used for the purpose.

To accomplish its purpose of protecting the switch point, the device of our invention is designed to be positioned upon the inner side of the track rail opposite to the point to be protected thereby and is arranged to be engaged by the inner surface of the car wheel flange and is formed to deflect the wheel laterally and in the direction of switching a distance sufficient to fully clear the associated wheel of endwise engagement with the switch point at its reduced end portion. Particular and important advantages of our improved form and arrangement of the switch point protector are, first, that upon loosening or accidental displacement the arrangement and form of the parts is such that they will be displaced away from the flange-way, and second, that the application of the device to the rail as indicated, in no way reduces, narrows or obstructs the gauge of the track structure; both of which important and particular advantages eliminate the danger factor present in many forms of devices heretofore proposed for the purpose.

The device of the present invention will be more fully understood by reference to the accompanying drawings wherein like reference characters are applied to the corresponding parts in the several views.

In the drawings:

Fig. 1 is a plan view of a railway switch structure of the split-switch type, having our improved protector installed to cooperate therewith.

Fig. 2 is a plan view showing a portion of the track rail with the improved protector secured in operating relation thereto.

Fig. 3 is a vertical cross sectional view taken on line A—A Fig. 2 and

Fig. 4 is a view of the protector member in side elevation.

The improved protector device of our invention comprises a deflector member 1, adapted as illustrated in Fig. 1 to be secured to the inner or flange-way side of the inner track rail 2 opposite to and in advanced relation to the switch point 3 to be protected. The switch structure, as illustrated, further includes the inner movable rail or switch point 4, suitably connected by a cross rod 5 to the protected point 3, the opposite main track rail 6 and turnout rails 7 and 8, the latter being continuous with the inner main rail 5 at the turnout.

The switch point protector member of our invention as indicated at 1 may be preferably cast of manganese or high grade alloy steel having a body portion provided at its mid-section with bolt apertures 9 to receive the securing bolts 10 for securing the protector member to the track rail 2. Upon its inner and upper longitudinal edge portion the protector member is provided with an upwardly and longitudinally extending deflecting flange 12 having the inner surfaces of its end portions angularly contoured at 15—15 to be outwardly flared with relation to the track rail head and disposed in spaced relation thereto to be engaged by the inner side surface of the car wheel flange for deflecting the latter outwardly, or in the direction of switching, sufficient to clear the associated wheel of engagement with the switch point at its reduced end portion. At its outer longitudinal edge portion the protector member is formed with a shoulder 17 having 90 bearing engagement with the underside or fishing surface of the rail head and, intermediate of the flange 17 and the deflecting flange 12, the body of the protector is longitudinally grooved or concave in cross section, thereby to provide ample clearance beneath the wheel flange with proportionate lessening of the danger factor incident to possible obstruction of the flange-way.

In further accordance with our invention, the protector member is of similar formation above and below a central horizontal plane defined by the axes of the bolt apertures from which it results that the protector member is reversible to provide for the renewal of the active surfaces when one of the deflecting flanges becomes worn. In accordance therewith, the lower section of the protector member is formed at its inner lower edge portion with the deflecting flange 110

12' having its outwardly directed end surfaces flared at 15' and is formed at its outer edge portion with a longitudinally extending shoulder 17' and has the intermediate portion 5 between the shoulders longitudinally grooved corresponding to the upper portion. To allow of this reversible form and to provide proper bearing for the deflecting member, a cast steel bearing insert or spacing block 20 is interposed between the protector member and the track rail and is of a contour generally complementary to the contour of the surfaces of the protector member and track rail engaged thereby, thus providing a 10 rigid support for the protector member. As indicated, the spacing member or block at its lower side has bearing support upon the rail base flange and its vertical web engaging portion is provided with apertures 19 to receive the securing bolts 10. The latter are threaded, as shown, at their inner ends to receive the usual securing nuts 20 with lock washers 21 interposed between the nuts and the inner face of the protector member. Interposed 15 between the heads 22 of the bolts 10 and the track rail web, suitable lock washers 23 are interposed, having at their upper ends horizontal portions 24 closely overlying the bolt head to prevent turning thereof. 20 As best shown in Fig. 4, the end portions of the deflecting flanges may desirably be rounded off to avoid objectionable sharp corners.

We have thus produced an improved 25 switch point protecting device of simple and strong construction adapted successfully to withstand the severe stresses imposed thereon by the engagement of the car or locomotive wheel and which, in its operation, will deflect the wheel in the direction of switching a distance sufficient to clear the extreme 30 end portion of the switch point, thereby relieving the latter of the initial shock and the application of switching pressures at the extreme point or reduced portion. The improved device is further of a design and arrangement possessing important safety factors in that upon loosening of the securing bolts, the allowable displacement is away 35 from the flange-way and the device as installed avoids reducing or obstructing the gauge of the track structure. The flaring of the deflecting flange at each of its end portions provides for non-interference with 40 the traffic in both directions and the device is, accordingly, particularly adapted for use in terminal and switching yards where it operates to effect substantial economy as related to the maintenance of switching structures in the protection of the relatively costly 45 switch point parts. The reversible design provides for additional economy as related thereto and the employment of the associated spacing blocks allows of readily accommodating the protector member to va-

ried rail sections by employing spacing blocks conforming to the specific rail sections.

As will be understood, varied modifications of the several features of our improved 70 switch point protector may be made without departing from the scope of the invention as defined in the appended claims. It is, therefore, intended that all matter herein shall be interpreted as illustrative and not in 75 a limiting sense.

Having described our invention, we claim:

1. A railway switch structure including the main rails and a movable switch point operatively associated with one of the main 80 rails, of a protector member therefor positioned at the inner side of the other or opposite rail, said protector member having its upper portion formed with an upwardly and longitudinally extending deflecting 85 flange having its outwardly directed surface at its end portions inwardly flared and positioned to be engaged by the inner flange surface of a wheel for deflecting the associated wheel to clear the end portion of the switch 90 point and having its lower portion correspondingly formed to be reversible and means for securing the protector member in position.

2. A railway switch structure including 95 the main rails and a movable switch point operatively associated with one of the main rails, of a protector member therefor positioned at the inner side of the other or opposite rail, said protector member having its 100 upper portion formed with an upwardly and longitudinally extending deflecting flange having its outwardly directed surface at its end portions inwardly flared and positioned to be engaged by the inner flange 105 surface of a wheel for deflecting the associated wheel to clear the end portion of the switch point and having its lower portion correspondingly formed so as to be reversible in position, a spacing member interposed between the protector member and the track rail providing bearing support for the 110 protector and securing bolts fitted to apertures in the protector member and rail for clamping the former in position.

3. A railway switch structure including 115 the main rails and a movable switch point operatively associated with one of the main rails, of a protector member therefor positioned at the inner side of the other or opposite rail, said protector member having its upper portion formed with an upwardly and longitudinally extending deflecting flange having its outwardly directed surface at its 120 end portions inwardly flared and positioned to be engaged by the inner flange surface of a wheel for deflecting the associated wheel to clear the end portion of the switch point and with an outer shoulder engaging the underside of the track rail head and having a 125 130

longitudinal flangeway groove intermediate of the deflecting flange and said shoulder and said deflector member having its lower section correspondingly formed to be reversibly operative, a spacing member interposed between the protector block and the track rail to provide bearing support for the protector, said spacing block having engaging surfaces formed of complementary contour to the block and the rail section and means for securing the protector and spacing members to the rail.

4. A railway switch structure including the main rails and a movable switch point operatively associated with one of the main rails, of a protector member therefor, positioned at the inner side of the other or opposite rail, said protector member having its upper portion formed with an upwardly and longitudinally extending deflecting flange

having its outwardly directed surface at its end portions inwardly flared and positioned to be engaged by the inner flange surface of a wheel for deflecting the associated wheel to clear the end portion of the switch point 25 and with an outer shoulder engaging the underside of the track rail head and having a longitudinal flange-way groove intermediate of the deflecting flange and said shoulder, said securing means comprising bolts fitted 30 to apertures in the protector and spacing members and rail and a lock washer element interposed between the bolt head and rail and provided with a portion overlying the former.

Signed at Jersey City, in the county of Hudson and State of New Jersey, April A. D. 1925.
